UNITED STATES PATENT OFFICE.

EDMUND HOFFMAN, OF BRIDGETON, NEW JERSEY, ASSIGNOR TO HIMSELF AND CHARLES E. E. WHITELEY, OF BRIDGETON, NEW JERSEY, HENRY WHITELEY, OF PHILADELPHIA, PENNSYLVANIA, AND WILLIAM G. WHITELEY AND ROBERT P. FRIST, OF WILMINGTON, DELAWARE.

NECK-FORMING TOOL.

SPECIFICATION forming part of Letters Patent No. 714,304, dated November 25, 1902.

Application filed July 31, 1900. Serial No. 25,373. (No model.)

To all whom it may concern:

Be it known that I, EDMUND HOFFMAN, a citizen of the United States of America, residing in Bridgeton, in the county of Cumberland, in the State of New Jersey, have invented a certain new and useful Improvement in Neck-Forming Tools, of which the following is a true and exact description, reference being had to the accompanying drawings, which

10 form a part thereof.

My invention relates to the construction of tools for forming the necks and lips of bottles, and has for its object to provide a tool of simple and efficient construction and which is 15 adapted for forming bottle-necks with outwardly-extending lugs adapted to make a bayonet or similar joint with properly-formed caps; and my invention consists in combining in a neck-forming tool a spindle adapted to 20 enter and form the inside of the neck with a freely-rotatable lip-forming annulus turning on the spindle and having outwardly-extending recesses formed in its edge and also a pair of jaws adapted to form the neck of the bot- 25 tle beyond the lip and formed with inwardly-extending flanges, which when the jaws are closed together extend over the recesses in the lip-forming annulus and are substantially flush with the inside of the annulus. By 30 preference I form on the spindle an annular enlargement, over which the rotatable annulus fits, the enlargement serving to mold the extreme end of the bottle-neck.

Reference being now had to the drawings 35 which illustrate my invention, Figure 1 is a side elevation, partly in central longitudinal section, of my improved tool. Fig. 2 is a longitudinal section on the line 2 2 of Fig. 1; Fig. 3, a detached view of the rotating annulus 40 shown on the same section as in Fig. 1. Fig. 4 is an end view of the annulus. Fig. 5 is an elevation of the bottle-neck molded on the tool, Fig. 1. Fig. 6 is a cross-section through the lip of the bottle on the line 6 6 of Fig. 5. Fig. 7 is a side elevation, partly in central 45 longitudinal section, of a modified form of tool embodying my invention; Fig. 8, a longitudinal section on the line 8 8 of Fig. 7;

Fig. 9, an end view of the spindle and annulus shown in Fig. 7; Fig. 10, a perspective view of the rotating annulus; Fig. 11, a longitudinal section through the annulus on the line 11 11 of Fig. 9; Fig. 12, an elevation of a bottle-neck formed on the tool shown in Fig. 7, and Fig. 13 a cross-section through the 55 lip of the bottle on the section-line 13 13 of Fig. 12.

A indicates a U-shaped spring, to which are attached the jaws B B, these jaws being formed, as shown, with perforations B' B' for 60 guide-pins connected with the spindle, recesses B², formed to clear the rotating lip-forming annulus, and inwardly-projecting flanges B³ B⁴, the faces B³ of which fit over the top of the annulus, while the faces B⁴ 65 when closed together are substantially flush with or rather tangent to the inner forming-surface of the annulus.

B⁵ and B⁶ are bead-forming grooves in the jaws B and B⁷, the surface giving shape to 70 the neck of the bottle lying beyond the beads.

C is the spindle of the tool, which, as shown, has a threaded end C', extending through a perforation in the spring A, to which it is attached by the nuts D and D'. 75

C⁶ indicates the other or free end of the spindle, which extends into and forms the inside of the bottle-neck, and, as shown, the spindle at the base of the portion C⁶ is formed with an annular flange C⁴, having a curved 80 outer face, (indicated at C⁵), against which the end of the bottle abuts and by means of which the extreme lip is formed. Below this flange C⁴, I have shown a somewhat-enlarged section C³, and below this a spindle-section C², 85 to which is firmly secured a block E, from which extend the guide-rods E', which extend through the perforations B' in the jaws and serve to keep the spindle and jaws in substantially fixed relationship to each other. 90

F is a rotatable lip-forming annulus which, as shown, fits on the portions C³ and C⁴ of the spindle and is held in position—that is, prevented from moving longitudinally—by the block E. The inner wall F' of the annulus 95 F forms the extreme lip of the bottle on the

outside and is formed with outwardly-extending lug-molding recesses, (indicated at F^2), over which, as already stated, the faces $B^3 B^4$ of the jaws extend when they are closed together and into which enough of the glass of the bottle-neck is forced to form such lugs as are indicated in Figs. 5 and 6 at G^4 , G indicating the bottle-neck, $G' G^2$ the beading, G^3 the plane annular surface lying between the beading and the lugs, $G^4 G^5$ indicating the extreme outer lip of the bottle and G^6 the portion of the lip lying between the lugs G^4 .

The operation of the tool is very simple. The bottle-neck in a plastic condition has inserted in it the spindle end C^6 , the extreme end of the neck being abutted against the curved surface C^5 . The jaws $B B$, which normally stand outward, are then closed together, pressing against the sides of the plastic material of the neck, and the bottle is then rotated in the tool until it assumes the exact conformation provided for by the operative parts of the tool, the "lip," so to speak, of the bottle being molded in the rotatable annulus F , which turns in the tool as the bottle turns, so that the portions of the glass which are pressed out into the recesses F^2 are smoothed down to reproduce the exact shape and exact arrangement of the recesses in the annulus. When the molding is complete, the jaws $B B$ are permitted to open, and the bottle is then readily removed.

The modified tool shown in Figs. 7 to 11 is one which differs from the tool already described in that it is adapted to mold the neck, and particularly the lip, of the bottle by pressing the plastic glass inward to a greater extent than is the case in the first-described tool, the most striking difference being that in the use of the first tool the bottle-neck is of about the diameter of the wall F' of the annulus F and the lugs on the lip are formed by portions of the glass being pressed outward, while in the modified tool the bottle-neck is of about the diameter of the portion f^2 of the annulus and the lugs are formed by pressing the plastic glass inward around the lugs, the lugs themselves being "formed," so to speak, from portions of the glass which are allowed to remain in substantially the position in which they are presented to the tool. In this modified tool the recesses which mold the lugs

are indicated at f^2, f' indicating the inner surfaces of the lip-forming annulus. The bottle-neck formed by the modified tool is shown at 55 G^x , Fig. 12, the beading $G' G^2$ being substantially identical with the beading on the bottle-neck G , the extreme lip G^5 being also substantially identical, the plane annular band between the beadings and the lugs being in the 60 modified neck indicated at G^8 , the lugs at g^4 , and the space between the lugs at g^6 . By comparing the two bottle-necks it will be seen that the portions $g^8 g^6$ are much more deeply indented than the portions $G^8 G^6$, as shown 65 in Fig. 5.

The operation of the modified tool is the same as that of the tool first described except in the degree of displacement which is effected in the forming of the bottle-neck. 70

Having now described my invention, what I claim as new, and desire to secure by Letters Patent, is—

1. A neck-forming tool for bottles having a spindle provided with an end adapted to enter and assist in forming a bottle-neck, in combination with a freely-rotatable lip-forming annulus, as F , turning on the spindle and having radially outwardly extending lug-forming recesses, as F^2 , in its edge and a pair of jaws, 75 as $B B$, adapted to form the bottle-neck in the rear of the lip, said jaws having flanges, as $B^3 B^4$, which when closed extend over the recesses substantially flush with the walls of the lip-forming annulus. 85

2. A neck-forming tool for bottles having a spindle provided with an end adapted to enter and assist in forming a bottle-neck and an annular enlargement C^4 having a curved upper face C^5 in combination with a freely-rotatable lip-forming annulus, as F , turning on the part C^4 of the spindle and having radially outwardly extending lug-forming recesses, as F^2 , in its edge, and a pair of jaws, 90 as $B B$, adapted to form the bottle-neck in the rear of the lip, said jaws having flanges, as $B^3 B^4$, which when closed extend over the recesses substantially flush with the walls of the lip-forming annulus. 95

EDMUND HOFFMAN.
